UNITED STATES PATENT OFFICE.

MELLEN BRAY, OF NEWTON, MASSACHUSETTS.

IMPROVEMENT IN THE MANUFACTURE OF HOLLOW RIVETS.

Specification forming part of Letters Patent No. 140,881, dated July 15, 1873; application filed March 17, 1873.

To all whom it may concern:

Be it known that I, MELLEN BRAY, of Newton, in the county of Middlesex and State of Massachusetts, have invented an Improved Hollow Rivet, and a process of making the same, of which the following is a specification:

My improved rivet is formed by first making a piece of tube with a closed end, of the proper length to make both the body of the rivet and the head, by drawing up the same from a piece of sheet metal by a mode of operation similar to that by which articles of a cylindrical tubular form are made, as is set forth in the Letters Patent reissued to me January 28, 1873, for dies for forming sheet-metal ware. This piece of tube is then set in a holding-die with the closed end outward, and projecting from the die to an extent sufficient to form the head of the rivet. A mandrel is placed inside of the tube to support that part of it which is in the die, and is to form the body of the rivet. Either upon the outside or the inside of this projecting portion of the tube I place a second piece of tube, which, being upset with the main portion, furnishes the material for making the head much larger than could otherwise be made. The projecting portions of the tubes are then upset by a die coming down upon it, which first causes the sides to bulge out, and then to be flattened down upon the lower die, and shaped into the usual form of head. This is very important in making rivets to be used in leather, cloth, and other flexible materials, where a small head would be liable to be drawn through.

When this supplementary thickness of tube to form the head is placed within the main tube the outer end of it need not be closed; but in practice I have found it easiest, with my present machinery, to produce the enlarged head by placing the supplementary piece of tube upon the outside; but I have also made rivets with the supplementary tube inside with complete success.

Figure 1 is the closed tube from which the rivet is to be formed, shown in section. Fig. 2 is the supplementary tube, which is placed

upon Fig. 1 to furnish the material to form an enlarged head. Fig. 3 is a section through the forming-dies with the tubes placed together in them and in the position to be upset. Fig. 4 is a section of the tube with the supplementary tube placed inside. Fig. 5 is a section of the rivet ready for use; and Fig. 6 shows its application to use.

A is the piece of tube from which the main body of the rivet is formed. B is the supplementary piece to form the head, which is placed on the outside of A, as is seen in Fig. 3; and B' is the supplementary tube, placed inside of A, as seen in Fig. 4. C C' is the holding-die, made in two parts, one of which, C, is fixed; and the other, C', is movable, so as to open to release the rivet after it is formed. They are held together by devices not shown; and the part C' is pressed away from the fixed part C by the spring D. E is the bed for the die C C', to which the fixed part C is held in a fixed position by the dowel-pin F. The opening in the die C C' is large enough to allow the tube A to be slipped in freely. G is a mandrel of the proper size to fit the inside of the tube A, and is made to slide vertically through the bed E, and is concentric with the hole in the dies. It sets in a guide-piece, H, and is held up by the spring I.

When the several parts are in the position shown in Fig. 3 the movable heading-die J is brought down upon the projecting portions of the tubes until the parts are brought to the positions shown by the dotted lines, which produces the rivet shown in Fig. 5. The action of the heading-die is to first cause the projecting portions of the tubes A and B to bulge out laterally, and then to be flattened into the head, as is shown.

When the supplementary tube is placed inside, as is shown in Fig. 4, the mandrel G extends upward to meet the lower end of the tube B', and remains fixed at about the height of the top of the die C C'.

The rivets are to be clinched by a punch in the manner similar to that now employed to clinch common eyelets, as is seen in Fig. 6.

I claim—

1. In the process of forming a hollow rivet, by upsetting the end portion of a closed tube, the combination, with the closed end of the tube, of a secondary or supplementary piece of tube, to be upset to furnish additional material to form the head of the rivet, substantially as described.

2. The hollow rivet, formed by the process herein described, as a new manufacture.

Executed February 24, 1873.

MELLEN BRAY.
